UNITED STATES PATENT OFFICE.

GUS JORDAHL, OF PALM BEACH, FLORIDA.

FLOATING DEVICE.

1,341,272.

Specification of Letters Patent. Patented May 25, 1920.

Application filed June 26, 1919. Serial No. 306,809.

To all whom it may concern:

Be it known that I, Gus JORDAHL, a citizen of the United States, and a resident of Palm Beach, in the county of Palm Beach 5 and State of Florida, have invented a new and Improved Floating Device, of which the following is a full, clear, and exact description.

This invention relates to life preservers, or 10 floating devices, and has for an object to provide a device wherein a proper supporting member is provided when wanted and a light package when not wanted.

Another object is to provide a device 15 which may be tied around the body or fastened in a number of ways without affecting its usefulness.

A further object of the invention is to provide a floating device for amusement purposes or life saving purposes which may be 20 folded into a minimum sized package when not in use, but may be greatly distended in use.

In the accompanying drawing:

25 Figure 1 is a view of a figure with an embodiment of the invention applied thereto.

Fig. 2 is a side view of the device shown in Fig. 1.

Fig. 3 is a cross section through Fig. 2 on 30 line 3—3.

Referring to the accompanying drawing by numerals, 1 indicates the body of the de-

vice which is formed with a closed end 2 and an open end 3. The body may be made from any desired material, as for instance 35 some good grade of textile fabric. The device may be made of different shapes, but is preferably formed from a rectangular piece of cloth folded longitudinally along a central line and then the opposite edges connected by a line of stitching 4. End 2 is then closed by a line of stitching 5. This produces a long, slender, straight walled bag. When it is desired to use the device the body 40 is first thoroughly wet and then inflated by 45 blowing with the mouth, or by waving the device in the air with the open end 3 facing the direction of movement. After the device has been inflated it may be secured to the body in a number of different ways, as for 50 instance by being tied with a cord, or by passing the device around the body of the person using the device and tying the ends as shown in Fig. 1.

What I claim is:

A device to be used in learning to swim consisting of a long flexible open ended tube adapted to encircle the body of a wearer, and relatively narrow whereby when blown up its ends may be tied together thus serving the double purpose of holding the device 60 in place on a wearer and detaining the air as and for the purposes set forth.

GUS JORDAHL.
